UNITED STATES PATENT OFFICE.

EDWARD SARGENT, JR., OF NEW PHILADELPHIA, OHIO.

DESIGN FOR A DOUGH-BOARD.

SPECIFICATION forming part of Design No. 30,397, dated March 28, 1899.

Application filed March 2, 1899. Serial No. 707,531. Term of patent 7 years.

To all whom it may concern:

Be it known that I, EDWARD SARGENT, Jr., a citizen of the United States, and a resident of New Philadelphia, in the county of Tus-

carawas and State of Ohio, have invented and produced a new and original Design for Dough-Boards, of which the following is a specification, reference being had to the accompanying drawings, in which—

Figures 1, 2, 3, and 4 are respectively a top view, a bottom view, a side view, and a transverse section of a dough-board embodying my new design.

As shown in the drawings, the essential fea-

tures of my design are a flat board having a plane top surface, a corrugated bottom surface, and curved or rounding transverse beads at the ends.

Having thus described my invention, what I claim, and desire to secure by Letters Patent, is—

The design for a dough-board substantially as herein shown and described.

EDWARD SARGENT, JR.
